37 INVENTOR
ALBERT A. GORDON
Southgate, Tracy & Hawley
ATTORNEY'S

UNITED STATES PATENT OFFICE

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

LOOM DOBBY

Application filed July 24, 1930. Serial No. 470,497.

This invention relates to improvements in loom dobbies of the general type shown in my prior Patent No. 1,653,207, issued December 20, 1927.

In my prior patent, I have shown a double cylinder dobbay adapted for double index operation and having a gear-driven mechanism for positively rocking the lever-supporting frame of the dobbay in one direction. Movement in the opposite direction was under the control of a spring.

This yielding return action was found unsatisfactory, as the mechanism to be controlled was of substantial weight and the timing of the parts was found unreliable, when a spring was used for the return movement.

Furthermore, the special high links used as indicators interfered with the folding of the portions of the chain in storage.

It is the object of my present invention to provide driving mechanism so designed and constructed that the lever frame in a double cylinder dobbay will be moved positively in both directions, leaving no uncertainty in the operation thereof.

My invention further relates to arrangements and combinations of parts which will be hereinafter described and more particularly pointed out in the appended claims.

A preferred form of the invention is shown in the drawings, in which

Fig. 1 is a side elevation of my improved dobbay;

Fig. 2 is a partial sectional plan view, taken along the line 2—2 in Fig. 1;

Fig. 3 is a sectional side elevation, taken along the line 3—3 in Fig. 2;

Fig. 4 is a partial sectional side elevation, similar to Fig. 3 but showing the parts in a different position;

Fig. 5 is a diagrammatic view, indicating the driving mechanism for certain parts;

Fig. 6 is a plan view, looking in the direction of the arrow 6 in Fig. 1;

Fig. 7 is a sectional front elevation of certain parts, taken along the line 7—7 in Fig. 6;

Fig. 8 is a detail sectional elevation, taken along the line 8—8 in Fig. 7;

Fig. 9 is a detail sectional elevation, taken along the line 9—9 in Fig. 6;

Fig. 10 is a plan view of a control lever, and

Fig. 11 is a side elevation thereof.

Referring to the drawings, my improved dobbay comprises the usual frame or support 10 on which rocking levers 11 are pivotally mounted. These levers are connected by a link 12 (Fig. 5) to a crank-pin 13 by which they are oscillated. The rocking levers 11 reciprocate the usual upper and lower knife bars 14 and 15.

Dobby levers 16 (Fig. 3) are pivotally mounted on the usual harness jacks 17 and support upper and lower dobbay hooks 18 and 19. The upper hooks are operated by alternate dobbay levers 20 through lifter rods 21 and the lower hooks 19 are operated by the upturned ends 22 of the remaining dobbay levers 20.

The dobbay levers 20 rest upon the adjacent ends of two sets of cylinder levers 24 and 25, pivoted on cross rods 26 and 27 in a rocking frame 28, which in turn is secured on a cross shaft 29.

Front and back dobbay cylinders 30 and 31 are rotatably mounted in the dobbay frame 10 and are provided with collars 300 and 310 fixed to the cylinder shafts adjacent loose gear wheels 32 and 33 to which they may be clutched one at a time and thus cause the corresponding cylinder to rotate, the cylinders rotating in opposite directions. The gear 33 is connected by a worm wheel 35 and intermittent worm 36 to an upright shaft 37 which is connected by bevel gears 38 (Fig. 5) to the shaft 39 which carries the crank pin 13.

When the rocking frame 28 is in the position shown in Fig. 3, the front set of cylinder levers 24 is in position for operation by the pattern chain on the cylinder 30, but when the frame 28 is rocked to the position shown in Fig. 4, the cylinder levers 25 are in position for engagement and control by the pattern chain on the rear cylinder 31.

For further details as to the construction and operation of the double cylinder dobbay,

reference is made to my prior patent above noted.

The position of the rocking frame 28 is determined by a pattern chain 40 on a pattern cylinder 41 which is loosely mounted on a stud 42 fixed in the frame 10. A worm gear 43 rotates on the stud 42 and is engaged by an intermittent worm 44 on the upper end of the shaft 37 previously described. A 10 sliding clutch member 410 is keyed to the hub of the cylinder 41 and may be moved to engage the gear 43 by suitable pattern chain elements.

The pattern chain 40 positions a pair of 15 rocking levers 45 and 46, pivoted at 47 and connected by adjustable links 50 and 51 (Fig. 1) to the oppositely disposed arms of a rocking lever 52 secured to the shaft 29 which supports the rocking frame 28.

20 When a ball or riser 55 on the pattern chain 40 comes under the rocking lever 45, the link 50 is depressed, moving the frame 28 to the position shown in Fig. 3 with the front set of cylinder levers 24 in operative 25 position.

When a riser 55 comes under the second 30 rocking lever 46, the frame 28 will be rocked in the opposite direction to the position shown in Fig. 4, with the cylinder levers 25 in operative position.

Positive operation of the rocking frame 28 is thus effected in both directions and no spring action is used, as a spring has been found to introduce uncertain timing and to 35 otherwise render the mechanism unreliable.

It is desirable that each pattern cylinder remain at rest when out of operative position and for this purpose a three-armed lever 60 (Fig. 2) is mounted on a fixed pivot 40 61 and is provided with a slotted arm 62 having an opening through which extends a stud 63 on the hub of the rocking lever 52. The other two arms 60^a and 60^b of the lever 60 engage clutch sleeves 64 and 65 by which 45 the gears 32 and 33 previously described may be alternately connected to the driving collars 300 and 310 for the cylinders 30 and 31.

The parts are so designed that the cylinder 50 30 will be rotated when the parts are in the position indicated in Fig. 3, while the cylinder 31 will be rotated with the parts in the position shown in Fig. 4.

The arms 60^a and 60^b are loosely pivoted 55 on the hub of the lever 60 and are held against stops 610 and 611 on the lever 60 by a spring 612 interposed between portions of the arms 60^a and 60^b. If movement of either clutch member 64 or 65 is obstructed, the corresponding arm will yield 60 temporarily and breakage is thus avoided.

Having described the details of construction of my improved dobby, it will be evident that a dobby made in accordance with 65 my present invention is under positive con-

trol of the pattern mechanism at all times and that disabling of the mechanism through failure in correct timing is effectively avoided.

Having thus described my invention and the advantages thereof, I do not wish to be limited to the details herein disclosed, otherwise than as set forth in the claims, but what I claim is:

1. A double cylinder loom dobby comprising two pattern cylinders, a set of dobby levers, a separate set of cylinder levers for each cylinder, both sets of cylinder levers cooperating with the single set of dobby levers, a rocking support for said levers, an actuating member, pattern-controlled means for moving said actuating member positively in both directions, and direct positive connections from said member to said rocking support, whereby positive movements of said support and cylinder levers in both directions to operative position are effected. 75

80 2. A double cylinder loom dobby comprising two pattern cylinders, a set of dobby levers, a separate set of cylinder levers for each cylinder, both sets of cylinder levers cooperating with the single set of dobby levers, a rocking support for said levers, an actuating member, pattern-controlled means for moving said actuating member positively in both 85 directions, and links positively connecting both ends of said actuating member to the corresponding ends of said rocking support, whereby positive movements of said support and cylinder levers in both directions to operative position are effected. 90

In testimony whereof I have hereunto affixed my signature.

ALBERT A. GORDON.
